INVENTOR

Victor J. Evans

ATTORNEY

WITNESS:

UNITED STATES PATENT OFFICE.

ERNEST VOGES, OF SAN ANTONIO, TEXAS.

RAZOR-BLADE SHARPENER.

Application filed October 7, 1922. Serial No. 593,017.

To all whom it may concern:

Be it known that I, ERNEST VOGES, a citizen of the United States, residing at San Antonio, in the county of Bexar and State of Texas, have invented new and useful Improvements in Razor-Blade Sharpeners, of which the following is a specification.

An object of this invention is to produce a simple, cheap and effective holder for safety razor blades, to permit of the stropping of the blades.

To the attainment of the foregoing, and other objects which will present themselves as the nature of the invention is better understood, reference is to be had to the drawing which accompanies and which forms part of this application.

In the drawing:—

Figure 1 is a side elevation of the improvement, with parts broken away and parts in section.

Figure 2 is an end view thereof.

Figure 3 is a sectional view on the line 3—3 of Figure 1.

Figure 4 is a perspective view of the jaw member.

Figure 5 is a perspective view of the plate provided with the tongue for spreading the jaws.

It will be noted as the nature of the invention is disclosed that the parts constituting the same are removably associated, so that the device may be readily cleaned and worn or broken parts replaced.

Referring now to the drawing in detail, the numeral 1 designates a handle which is preferably threadedly connected with the cross sectionally rounded end of what I will term a head member 2. The head member is co-extensive with the handle, and from its said rounded end 2, the same is elliptical in cross section, as indicated by the numeral 3. The elliptical body 3 is provided with a longitudinal slot 4 entering from one of its edges and communicating with a wider slot or opening 5. The body 3 is provided, at spaced intervals, upon its edge opposite that provided with the slot 4, with lugs 6, the said lugs passing through openings provided therefor in the rounded body portion 6 of a spring member. The member 6 has its side disposed inwardly with respect to each other, whereby the said sides provide jaws 7 respectively.

The head 3 has arranged therearound a compressible strip 8 which is also in contacting engagement with the inner faces of the jaws 7.

Also in contacting engagement with each of the jaws 7 there is a metal plate 9 of a cross sectional contour complementary to that of the jaws, the said plates 9 contacting with the strip 8. Each of the plates 9 has its upper edge centrally formed with an extension in the nature of a tongue 10, the said tongue passing through elongated slots arranged centrally in the rounded body portion 6 of the jaws 7. The tongues 10, when forced toward each other spring the jaws 7 away from each other, permitting a blade 11 to be received between the ends of the compressible element 8 and into the slots or openings 4 and 5. A release of the tongues will cause the jaws to force the compressible strip against the sides of the blade 11, thereby effectively holding the said blades in the device to permit of the stropping of the blade.

It is thought that the foregoing description, when taken in connection with the drawing will fully set forth the construction of the improvement, and it is further thought that the operation thereof will be apparent to those skilled in the art to which this invention relates.

Having described the invention, I claim:—

In a device for holding safety razor blades for the stropping thereof, a head having a body portion which is elliptical in cross section and which is provided with a longitudinal slot to receive a safety razor blade therein, a compressible sheet surrounding the head and projecting beyond the slotted edge thereof, a spring metal member having a cross sectionally rounded body portion disposed over the sheet, said spring member having its sides directed toward each other to provide jaws, means removably connecting the head to the jaw carrying member, plates on the inner sides of the jaws having central tongues projecting through openings in the body of the jaws, a handle removably connected to the head.

In testimony whereof I affix my signature.

ERNEST VOGES.
